The ornamental design for a work glove with slip-preventive palm, as shown and described.

DESCRIPTION

FIG. 1 is a palm-side perspective view of a work glove with slip-preventative palm showing my new design;

FIG. 2 is a backside perspective view thereof;

FIG. 3 is a palm-side elevation view thereof;

FIG. 4 is a top perspective view thereof;

FIG. 5 is a side perspective view thereof;

FIG. 6 is an other side perspective view thereof;

FIG. 7 backside elevation view thereof; and,

FIG. 8 is an enlarged detail view of the palm side showing the slip preventative palm.

While FIGS. 1-7 above illustrate a right hand work glove design of the present invention having a palm face comprising a slip-preventive palm, it is to be understood that the invention of this application includes a left hand work glove design having a slip-preventive palm, which glove would be illustrated as a mirror image of any or all of the views shown in FIGS. 1-7 herein.
